CLAIM

The ornamental design for an indoor plant cultivator as shown and described.

DESCRIPTION

FIG. 1 is a bottom perspective view of an indoor plant cultivator showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view of the indoor plant cultivator shown with the environmental structure of extension pipes. The broken lines depict portions of the indoor plant cultivator that form no part of the claimed design. The broken line showing of extension pipes in FIG. 8 show environmental structure only and form no part of the claimed design.
